UNITED STATES PATENT OFFICE.

WILLIAM A. LORENZ, OF HARTFORD, CONNECTICUT.

DESIGN FOR A CAN OR JAR.

SPECIFICATION forming part of Design No. 35,066, dated September 10, 1901.

Application filed August 12, 1901. Serial No. 71,842. Term of patent 14 years.

To all whom it may concern:

Be it known that I, WILLIAM A. LORENZ, a citizen of the United States, residing in Hartford, in the county of Hartford and State of Connecticut, have invented a new and original Design for Cans or Jars, of which the following is a specification.

My design relates to the external contour of cans, jars, and similar receptacles.

In the drawings, in which similar numerals designate corresponding parts, Figure 1 is a top view, and Fig. 2 a side view, of a can or jar embodying my design.

The body 10 of the can or jar is substantially cylindrical and is provided with a shoulder 11, which reduces the said body in diameter to form a comparatively short and approximately cylindrical zone 12, above which is the circumferential groove 13. That groove is approximately semicircular in cross-sec-

tional outline and is surmounted by a narrow and substantially cylindrical band or rib 14, which is smaller in diameter than the zone 12. The circumferential corner 15, formed by the intersection of the zone 12 and the groove 13, is slightly rounded, the whole forming a graceful and pleasing contour.

Having described my invention, what I claim as new, and desire to secure by Letters Patent, is—

The design for a can or jar substantially as shown and described.

In testimony whereof I have signed my name to this specification in the presence of two subscribing witnesses.

WILLIAM A. LORENZ.
